CLAIM

The ornamental design for a wearable device with graphical
user interface, as shown and described.

DESCRIPTION

The file of this patent contains at least one drawing/photograph
executed in color. Copies of this patent with color
drawing(s)/photograph(s) will be provided by the Office
upon request and payment of the necessary fee.

FIG. 1 is a front view of a wearable device with graphical
user interface showing the claimed design;

FIG. 2 is a front view of another embodiment thereof; and,
FIG. 3 is a front view of another wearable device having a
display screen with the graphical user interface of FIG. 1
applied to the display screen. The graphical user interface
design of FIG. 2 may be similarly applied thereto.

The outer broken lines in the figures show a wearable device
having a display screen, and form no part of the claimed
design. The other broken lines in the figures show portions
of the graphical user interface that form no part of the
claimed design.
